UNITED STATES PATENT OFFICE.

JOHN BAGLEY, OF TACOMA, WASHINGTON.

GRADER.

No. 846,278.

Specification of Letters Patent.

Patented March 5, 1907.

Application filed July 10, 1906. Serial No. 325,481.

To all whom it may concern:

Be it known that I, JOHN BAGLEY, a citizen of the United States, and a resident of Tacoma, in the county of Pierce and State of Washington, have invented a new and Improved Grader, of which the following is a full, clear, and exact description.

The invention relates to graders, and is especially useful in connection with devices of this character intended for operation in hard ground, such as shale.

The object of the invention is to provide a grader which is simple, strong, and durable in construction and which presents a plurality of blade edges.

A further object of the invention is to provide removable teeth for a device of the character described which are peculiarly adapted for use in hard or stony ground.

20 The invention consists in the construction and combination of parts to be more fully described hereinafter and particularly pointed out in the claims.

Reference is to be had to the accompanying drawings, forming a part of this specification, in which similar characters of reference indicate corresponding parts in all the figures.

Figure 1 is a perspective view of the grader, Fig. 2 is a longitudinal vertical section of a 30 part of the invention, and Fig. 3 is a perspective view of a tooth-bar.

Referring more particularly to the drawings, I provide side plates 1, which lie in vertical planes parallel to each other and are 35 imperforate to prevent the escape of earth through the sides of the device. The plates are of sheet-steel or other similar suitable material. To the rear end of the side plate is fastened by riveting or otherwise an end plate 2, comprising a bucket. The end plate is curved about a horizontal axis and presents a concavity toward the front of the grader. I prefer to attach the end plate 2 to the side plates 1 by means of angle-brackets 3, curved 45 to conform to the end plate and rivets 4. At each transverse edge of the end plate is a scraper-blade 5, which extends transversely between the side plates 1 and is set with a slight inclination outward to cause it to take 50 hold on the ground. The projecting sides of the blades are beveled to present cutting edges adapted to scrape up the surface of the ground as the grader is drawn along upon the same. The scraper-blades 5 are secured to 55 the end plate 2 by means of angle-brackets 6, which are riveted, respectively, to the side

plates and the scraper-blades. The angle-brackets may be mounted either inside of or outside of the side plates. Between the front ends of the side plates extends a cross-brace 7, holding them rigidly together at the proper distance.

I provide a bail 8, which is connected to the front ends of the side plates 1, adjacent to either edge thereof, by means of plates having offset ends, the plates being riveted to the side plates, while the ends of the bail are pivoted between the offset ends of the plates and the side plates. To the bail 8 is connected the draft mechanism, which may be actuated by power of any sort suitable for the purpose. For attaching to the grader the draft mechanism for hauling the grader backward staples 10, having eyes 11, are riveted to the end plate 2 at the rear side thereof.

25 In order to make the grader particularly adaptable for use in hard ground, I provide a plurality of tooth-bars 12, having sharpened or pointed ends or teeth 13 and split shanks 14. The tooth-bars may be mounted upon 30 the scraper-blade, as shown most clearly in Fig. 1, and secured thereto by rivets or bolts 15.

The split formed in the shank 14 is so fashioned with an inclined bottom that it fits closely upon the scraper-blade. The 35 shank of the tooth-bar has an extension 16, which is slightly curved and is adapted to extend beyond the scraper-blade and onto the end plate or bucket and to be riveted to the same. It will be understood that there 40 is a double advantage in this construction, as it not only more securely holds the teeth in place, but at the same time rigidly attaches the scraper-blade to the bucket. The tooth-bars adapted to be attached at the outermost ends of the scraper-blades are not provided with the extension 16, for the reason 45 that the scraper-blades extend laterally beyond the bucket, and therefore this extension would be unnecessary. The rivets for 50 attaching the end tooth-bars in place pass through the tooth-bar shank, the scraper-blade, and the bracket 6. The teeth may be 55 of any suitable form which is adapted to enter hard ground and break up the same into small fragments adapted to be scraped into 60 the bucket, but are preferably of the form shown in Figs. 2 and 3. If so desired, the tooth-bars may be attached by means of 65 bolts instead of rivets, and in this case they may be removed and replaced when necessary.

In using the apparatus it is adjusted upon the ground and drawn in the direction toward which the concavity of the bucket faces. The lower blade scrapes up the earth, 5 and if it bears teeth these assist in breaking up shale or the like, and the material is gathered into the bucket and is borne along with the grader. When the end of the haul is reached, the grader is drawn back by 10 the draft device attached at the back of the bucket and a new haul or drag is made. The grader may be reversed, and, owing to the construction employed, the blades or the teeth thereupon may be readily removed for 15 repair.

Having thus described my invention, I claim as new and desire to secure by Letters Patent—

1. A grader having a bucket presenting a plurality of blades having cutting edges, one of said blades having a plurality of teeth mounted thereupon and projecting beyond said edge.
2. In a grader, a bucket having an end plate, blades secured adjacent to the edges of said end plate, one of said blades having teeth with split shanks mounted thereupon,

said shanks and said teeth having extensions adapted to be secured to said end plate.

3. A grader having side plates, and an end plate curved about a horizontal axis and mounted between said side plates, blades secured to the horizontal edges of said end plate, and teeth having split shanks mounted upon one of said blades with the teeth projecting beyond the edge thereof.

4. A grader having side plates, means rigidly connecting the front ends thereof, an end plate extending between the side plates and curved around a horizontal axis, presenting the concave side to the front of the grader to form a bucket, blades secured to the longitudinal edges of said end plate, and teeth having split shanks mounted upon one of said blades and extending beyond the edge thereof, said shanks having extensions rigidly secured to said end plate.

In testimony whereof I have signed my name to this specification in the presence of two subscribing witnesses.

JOHN BAGLEY.
